UNITED STATES PATENT OFFICE.

WILLIAM B. SAVAGE, OF WEST SOMERVILLE, MASSACHUSETTS.

DESIGN FOR A CHAIR.

SPECIFICATION forming part of Design No. 16,646, dated April 20, 1886.

Application filed March 6, 1886. Serial No. 194,350. Term of patent 7 years.

To all whom it may concern:

Be it known that I, WILLIAM B. SAVAGE, a citizen of the United States, residing at West Somerville, in the county of Middlesex and State of Massachusetts, have invented and produced a new and original Design for an Arm-Chair, of which the following is a specification, reference being had to the accompanying drawing, forming part thereof.

- 10 The leading features of my new and original design comprise the representation, in a chair, of a back thereof having the shape and configuration of the ordinary flax-spinning wheel, with a head-rest upon the superior arc 15 of said wheel, illustrating the spool and flier of such a wheel, and the representation in the body portion of the chair beneath the seat, of the treadle of a flax-spinning wheel, in the place of the ordinary cross-brace, as well as 20 the conventional representation of other well-known parts of the spinning-wheel—such as the flier-standards, wheel-standards, treadle-pitman, &c.—in the arms, posts, and supports of the chair.
- 25 In the drawing; A represents the chair-back having a central hub, a, from which radiate the spokes b to the periphery or rim c. Upon the superior arc or segment of the rim is placed the ornamental rest H, consisting of an up- 30 right in the form of the spool, bearing at its upper extremity the ordinary spindle and flier. Arms B, modeled to represent the wheel-standards, spring from a suitable point in the periphery of the wheel-back and reach for- 35 ward to cover the posts C, arising from the seat portion of the chair in the ordinary manner, and modeled to represent the flier-standards. Beneath the seat is disposed the cross-brace E, comprising the three members e, the 40 same being in conventional representation of the treadle of a flax-spinning wheel whose pitman passes upward from the extremity of

the brace in the form of a straight bar or standard, G, at the rear of the back. Posts D, modeled to represent the wheel-standards, ex- 45 tend downward, as usual, from the seat P, and rungs or stretchers F, in the form of a distaff, complete the design. It will thus be apparent that I give to a chair a graceful as well as unique appearance, while at the same time 50 the use and durability of the same are in no wise impaired.

Having fully described my design, what I claim as new and original is—

1. In a design for a chair as herein shown and described, the design for the back thereof, consisting of the wheel A, having upon its superior arc the ornamental rest H, in conventional representation of the spindle and flier of a flax-wheel, as set forth. 6c

2. In a design for a chair as herein shown and described, the design for the back and arm thereof, the same consisting of the wheel A, the ornamental rest H, the arms B, in conventional representation of wheel-standards, 65 and posts C, in conventional representation of flier-standards, as set forth.

3. In a design for a chair as herein shown and described, the design for the body thereof, the same consisting of the seat P, having stand- 70 ards D, rungs or stretchers F, in the form of a distaff, cross-brace E, in the form of a treadle, as set forth.

4. The design for a chair as herein shown and described, the same consisting of the seat P, the back A, head-rest H, arms B, posts C and D, rungs F, cross-brace E, standard G, the whole modeled to represent a chair of conventionalized flax-spinning-wheel pattern, as 75 set forth.

WILLIAM B. SAVAGE.
